UNITED STATES PATENT OFFICE.

GEORGE REED ROGERS, OF PARKERSBURG, INDIANA, ASSIGNOR OF ONE-HALF TO GEORGE S. HARNEY.

CAR-COUPLING.

SPECIFICATION forming part of Letters Patent No. 447,259, dated February 24, 1891.

Application filed July 8, 1890. Serial No. 358,050. (No model.)

To all whom it may concern:

Be it known that I, GEORGE REED ROGERS, a citizen of the United States, residing at Parkersburg, in the county of Montgomery and State of Indiana, have invented certain new and useful Improvements in Car-Couplers; and I do declare the following to be a full, clear, and exact description of the invention, such as will enable others skilled in the art to which it appertains to make and use the same.

My invention relates to certain new and useful improvements in car-couplers and the nature of the invention will be understood from the following description, when taken in connection with the accompanying drawings, in which—

Figure 1 is a longitudinal section through two draw-heads, and Figs. 2 and 3 views in detail of my improved combined link and coupling-pin.

In the drawings, A A represent the draw-heads provided with the ordinary flaring mouth-pieces, the upper inner face of each draw-head being formed with inclines a, upon which the links ride as they enter the draw-head.

B B represent my improved links. Each such link is provided with a toggle C at one end, formed, preferably, at an angle of about thirty or forty degrees to the link. This toggle C serves as a coupling-pin, the toggle of one link engaging the link of the next car. Horizontally through such toggle I bore an opening b, through which a short shaft c is passed, said shaft having bearings in the side walls of the draw-head at a point near the forward end thereof, the position of the parts being such that the link will be pivoted in the expanded mouth of the draw-head. The normal position of the link is that shown in full lines in Fig. 1, wherein the link is shown as occupying a vertical position, with its end depending below the draw-head, the toggle C of each link being directly in line with the mouth of the draw-head, its upper end (which is notched, as at d) resting against

a slight incline e, formed upon the inner face of the draw-head.

It being desired to couple the cars, one link is raised until it occupies the position shown in dotted lines in Fig. 1, and the cars being then brought together the link so raised will strike against the toggle of the remaining link, which will be thereby forced back until the end of the link has passed over it, after which it will by its own weight return to its normal position, thus coupling the cars, the link thus coupled resting on shoulders f, formed upon the toggle.

To raise the link to a proper angle to accomplish the coupling as above described, and also to uncouple the cars without the necessity of the train-hand entering between the cars, mechanism is provided, two ways of accomplishing this end being shown. In one case I form the opening b in the toggle in an oval form, making its shaft also oval, and providing such shaft with a crank-arm f', the shaft extending beyond the side of the car. In the second case I connect the toggle by means of a link g with a bar h, such bar at its rear end being connected with a shaft i, this shaft being provided with a crank-arm j. Connected with shaft i by link k is a bar l, carrying at its rear end a spring m, which abuts against a cross-beam n and a shoulder o on the bar, this spring serving to return the parts to their normal position.

To uncouple the cars, that link the toggle of which is in use is turned until the link coupled to it can be withdrawn.

What I claim is—

The combination of the draw-head, the combined link and pin, the rock-shaft i, bar h, link g, rod l, spring m, and link k, all arranged and operating substantially as specified.

In testimony whereof I affix my signature in presence of two witnesses.

GEORGE REED ROGERS.

Witnesses:
